LOCK

Charles Kemp and Irving Kemp, New York,
N. Y., assignors to Kemp Lock Inc., New York,
N. Y., a corporation of New York

Application April 20, 1932. Serial No. 606,499

15 Claims. (Cl. 70—74)

This invention relates to door locks.

It is directed to the type of lock generally described in our co-pending application, Serial No. 516,576, filed February 18th, 1931, wherein a plurality of bolts are projected in a plurality of directions; and it is an object of this invention to generally improve a lock of the character described.

A further object of this invention is to provide a compact, strong and rugged anti-jimmy lock of the character described, having improved means for actuating the bolts, which shall comprise comparatively few and simple parts, be comparatively cheap of manufacture, smooth and positive in operation, easy to assemble and disassemble, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a rear view of a lock embodying the invention, with the rear cover plate removed and showing the parts in unlocked position;

Fig. 2 is a view similar to Fig. 1 but showing the parts in locked position;

Fig. 3 is a cross-sectional view taken on line 3—3 of Fig. 2;

Fig. 4 is a cross-sectional view taken on line 4—4 of Fig. 1;

Fig. 5 is a top plan view of the horizontal bolt; Fig. 6 is a side elevational view of the bolt shown in Fig. 5;

Fig. 7 is a top plan view of the actuating mechanism for the horizontal bolt; and

Fig. 8 is a side elevational view of the structure shown in Fig. 7.

Referring now in detail to the drawings, 10 designates a lock embodying the invention, adapted to be attached to a door adjacent the edge thereof, and 11 designates a keeper for the lock adapted to be attached to a door jamb. The lock 10 comprises a casing 12 having a front wall 13, top and bottom walls 14 and 15, an end wall 16 remote from the door edge, and an end wall 17 adjacent the edge of the door and provided with an opening 18 for slidably receiving a portion of the horizontal bolt 25, as will appear hereinafter.

The rear of the casing may be closed by a cover plate 20 resting on a ledge formed around the rear edge of the casing and screwed thereto by means of a screw 21. The inner surface of said front wall 13 is formed with a pair of parallel 60 guide walls 23 and 24 and slidably mounted between said guide walls is the horizontal bolt 25 shown in detail in Figs. 5 and 6 and provided with a central wall portion 26 slidably contacting said front wall 13.

Extending from said wall portion 26 toward the end wall 16, are a pair of aligned, flat arms 27 and 28; and projecting rearwardly from said portion 26 is a transverse wall 29. Adjacent said wall 29 the arms 27 and 28 are provided with 70 aligned ledges 30 and 31. Adjacent the outer end thereof, said arm 28 is formed with a ledge 32 on the same level as the ledges 30 and 31 and with a rearwardly projecting wall 33. The arm 27 is preferably somewhat longer than the arm 75 28 and is likewise provided with a ledge 34 on the same level as the ledges 30, 31 and 32, and with a rearwardly projecting wall 35 having a slot 36 on the inner end edge thereof.

For the purpose hereinafter appearing, said 80 rearwardly projecting wall 29 is provided with a pair of spaced symmetrically disposed projections or pins 37. Extending from said portion 26 of the horizontal bolt and projecting toward the wall 17 of the casing, is a bolt portion 40 adapted to 85 project through said opening 18, and forming with said portion 26, a shoulder 42 adapted to contact said wall 17 to limit the projecting movement of said horizontal bolt. Said horizontal bolt is further provided with a wall portion 45 extending rearwardly from one end of the wall portion 40, and a middle portion 46 extending from said wall 45 toward said wall 29. On opposite sides of said central portion 46, said horizontal bolt is provided with parallel rack portions 47, for 90 95 the purpose hereinafter appearing.

For projecting said horizontal bolt, there is provided a T shaped member 50 having a flat wall portion 50a slidably mounted on the ledges 30, 31, 32 and 34, and a rearwardly projecting wall 51 100 contacting said wall 29. Said portion 50a is further provided with rear edges 52 and 53 adapted to slidably contact the walls 33 and 35 of said arms 28 and 27 respectively. Fixed to said portion 50a is a tube 54 having a through opening 105 55 and a semi-cylindrical portion 56 projecting rearwardly toward said cover plate 20. A pin 55a having a head 56a, may also be fixed to wall portion 50a and adjacent said wall portion 51. Rotatably mounted on said front wall 13 is a 110

hand knob 58 to the inner end of which there is fixed an arm 59 provided with a pin 60 journaled within said opening 55.

It will now be noted that as the hand knob 58 is rotated, the member 50 will be caused to slidably move transversely of the longitudinal mid-section of the horizontal bolt 26, and said horizontal bolt may thus be moved longitudinally. A spring 62 having a central coiled portion 63 disposed about the pin 55a is provided with arms 66 and 67, the former contacting the front surface of wall 50a and extending into said slot 36 of the wall 35 and the latter arm contacting the wall 29. Said spring 62 serves to normally retain the horizontal bolt in fully retracted and fully projected positions, as shown in Figs. 1 and 2 respectively, of the drawings and further serves to retain member 50 from lifting off said ledges 30, 31, 32, 35.

20 The top and bottom walls 14 and 15 of the casing are preferably provided with aligned tubular portions 14a and 15a adjacent the end wall 17 and slidably mounted within said tubular portions are a pair of similar, symmetrically disposed vertical bolts 70, described and shown in detail in our said co-pending application, and each comprising a part 71 slidably mounted in one of said openings, and a U-shaped member 72 rotatably mounted on said member 71.

25 The tubular openings 14a and 15a are preferably square in cross-section, and the members 72 preferably each comprise an arm 74 of square cross-section, from which there extends a cylindrical portion 76 at the outer end of which there is formed a pinion 77. Extending from said arm 74 is a portion 75 likewise of square cross-section, and adapted to extend beyond the edge of the door. An arm 73 preferably of square cross-section extends from said portion 75 and is disposed parallel to said arm 74. The member 71 is provided with a cylindrical opening receiving said cylindrical portion 76, and is further provided with a slot 78 receiving a pin 79 fixed to and projecting from said cylindrical portion 76 to prevent 40 relative sliding movement between said members 71 and 72, and to limit rotation of said member 72 to 180° from the position shown in Fig. 1 to that of Fig. 2. Fixed to the inner ends of said members 71 are rearwardly projecting pins 80, 45 for the purpose hereinafter appearing. The front side of each member 71 is cut away as at 71a to expose the gear 77, and permit the same to mesh with one of the rack portions 47 or 48 as shown in Fig. 4.

50 The rear cover plate 20 is provided, for the purpose hereinafter appearing, with a pair of symmetrically disposed openings 82, and lying against the inner surface of said rear cover plate are a pair of similar, symmetrically disposed flat bolt actuating plates 83 having pins 84 at adjacent ends journaled within said openings 82. Said plates 83 are provided with slots 85 each receiving one of said pins 37 therethrough. Adjacent the outer ends thereof, said plates 83 are formed with small slots 87 receiving said pins 80. With the lock in position shown in Fig. 2, and the horizontal bolt projected, and the vertical bolts retracted into engagement with the keeper 11, as will appear hereinafter, the actuating plates 83 will be pivoted inwardly substantially into contact with one another. In such position the portions 73 of the bolt members 72 will be received within the tubular openings 14a and 15a and the pinions 77 will substantially contact one another.

75 For the purpose hereinafter appearing, the slot

85 in each plate has a portion 90 extending radially toward one of the pins 84 and with a portion 91 inclined outwardly away from the mid-section of the casing and toward the end wall 17. At the end of said portion 91, said slot 85 has another radially extending slot end portion 92. At the inner end of the slot portion 90 there is a slot portion 94 inclined away from the horizontal mid-section of the casing and toward the end wall 16, said slot portion 94 terminating in a short, 85 radially extending slot end portion 95.

80 The operation of the lock 10 will now be described. Beginning with the parts in unlocked position, as shown in Fig. 1, it will be noted that the pins 37 are at the extreme left ends of the slots 85 and within the portions 95 of said slots. 90 As shown in Fig. 1, further, the inner ends of the portions 73 of the bolt members 72 project within the tubular openings 14a and 15a so that no rotation of said parts 72 is possible in the position of said figure. Further, the rack portions 47 are disposed to the left of and are out of mesh with the pinions or gears 77, which are disposed somewhat closer to the mid-section of the casing than said rack portions. Further, as shown in Fig. 1, 100 the bolt parts 72 project inwardly of the end wall 17 so as not to project beyond the edge of the door.

Upon rotating the knob 58 for projecting the horizontal bolt 25 in a clockwise direction, looking 105 at Fig. 1, the member 50 will be reciprocated between the walls 33, 35 and 29 of said horizontal bolt, and the bolt will begin to move toward the right. During the first part of the movement, the pins 37 will move within the radially extending 110 portions 95 of the slots, without pivotal movement of the plates 83 or bolts 70.

115 Further projecting movement of the horizontal bolt will bring the pins 37 within the slot portions 94. During this part of the movement the plates 83 will pivotally move about said pins 37 away from each other, and away from the horizontal mid-section of the casing. Due to the engagement of said plates 83 with the pins 80, the bolts 70 will be moved a short distance 120 away from each other sufficiently to bring the inner ends of the arms 74 somewhat beyond the ends of the tubular portions 14a and 15a. This movement will bring the gears 77 in alignment with the rack portions 47 and substantially in 125 mesh therewith. Continued movement of the horizontal bolt to the right, will bring the pins 37 within the slot portions 90, said slot portions then being disposed parallel to each other and extending radially toward the pivot pins 84. 130 During this part of the movement, the plates 83 will not be rotated, but the racks 47 will engage the pinions 77 for rotating the members 72 180° about the axis of portions 76 to project said members beyond the edge of the door.

135 Further movement of the horizontal bolt will bring the pins 37 within the slot portions 91 for causing the plates 83 to be pivotally moved inwardly toward each other for moving arms 73 into engagement with the keeper 11. During 140 this last movement, the pinions will be out of mesh with the racks 47. Further movement of the horizontal bolt will bring the pins 37 within the radial slot portions 92 for further projecting the horizontal bolt without affecting the vertical 14. bolts.

145 As shown in Fig. 1, when the horizontal bolt is fully retracted, the pins 37 are within the slot portions 95 and are horizontally disposed. In this position, movement of the vertical bolts 15

either outwardly or inwardly is prevented. Also in the position of the parts as shown in Fig. 2 of the drawings, with the horizontal bolt fully projected, the pins 37 are in the slot portions 92 which are likewise horizontally disposed so as to prevent outward or inward movement of the vertical bolts. 5 and a projection on said first bolt extending through said slot, said slot in one position of said pivoted member having a portion parallel to the direction of movement of said first bolt, and portions at the ends of said first portion inclined to said first portion. 80

It will be further noted that in the beginning and ends of the strokes, the square shaped arms 10 74 of the U-shaped bolts are received within the tubular square openings 14a and 15a so as to prevent rotation of the bolt parts 72. In other words, beginning with the lock in the position shown in Fig. 1, the U-shaped vertical bolts must 15 be first moved outwardly before the bolt parts 72 can be rotated. A positive acting jimmy-proof lock is thus produced. 90

For the purpose hereinafter appearing, the portions 50a of the member 50 is formed at one 20 corner thereof with a beveled or inclined edge 57, and the upper wall 14 of the casing is provided with an inwardly extending projection 57a adapted to contact said edge 57 in the projected position of the horizontal bolt. With this construction, should the knob 58 be broken and the 25 arm 59 removed, the horizontal bolt nevertheless could not be pushed back to retracted position, thus providing additional safety for the lock. The lug or projection 57a on the casing contacting 30 the member 50, prevents retraction of the horizontal bolt without actuation of the hand knob or key. Obviously, in rotating the hand knob to retract the horizontal bolt from projected position, the member 50 will slidably move 35 with respect to the horizontal bolt so as to clear the lug 57a. 100

Preferably the upper and lower edges of the end wall 17 are grooved, as at 101, for receiving sides 75a of the bolt portions 75. 105

40 The strike 11 may comprise a wall 102 provided with an opening 103 for receiving one end 45 of said horizontal bolt 25, the upper and lower edges of said wall 102 being formed with grooves 105 for likewise receiving the inner sides 75a of 45 said portions 75. Extending from the wall 102 is a wall 104 adapted to be attached to the door jamb by screws, or in any other suitable manner. Extending from the upper and lower ends of said 50 wall 104 are walls 107 provided with square openings 108 for receiving the arms 73. Preferably, the inner surface 110 of said wall 102 is provided with recesses 111 adjacent the upper and lower ends thereof for receiving the inner sides 112 of said arms 73. 115

55 It will thus be seen that there is provided a device in which the several objects of this invention are achieved, and which is well adapted to meet the conditions of practical use. 120

As various possible embodiments might be made 30 of the above invention, and as various changes might be made in the embodiment set forth, it is to be understood that all matter herein set forth or shown in the accompanying drawings is to be interpreted as illustrative and not in a 35 limiting sense. 125

Having thus described our invention, we claim as new and desire to secure by Letters Patent:—

1. A lock comprising a casing, a bolt slidably mounted therein, means for projecting said bolt from said casing, a second bolt, and means for moving said second bolt in a direction transverse to the direction of movement of said first bolt, said means comprising a member pivoted within said casing and having an operative connection with said second bolt and provided with a slot, 130 and a projection on said first bolt extending through said slot, said slot in one position of said pivoted member having a portion parallel to the direction of movement of said first bolt, and portions at the ends of said first portion inclined to said first portion. 135

2. A lock comprising a casing, a bolt slidably mounted therein, means for projecting said bolt from said casing, a second bolt, and means for moving said second bolt in a direction transverse to the direction of movement of said first bolt, said means comprising a member pivoted within said casing and having an operative connection with said second bolt and provided with a slot, and a projection on said first bolt extending through said slot, said slot in one position of said pivoted member having a portion parallel to the direction of movement of said first bolt, and portions at the ends of said first portion inclined to said first portion, and portions at the ends of said inclined portions, extending radially with respect to the pivot for said pivoted member. 140

3. In a lock, a casing, a bolt mounted for reciprocation in said casing, a second bolt, means for projecting said first bolt, and means for causing sliding movement, then rotary movement, and then sliding movement again of said second bolt during the projection of said first bolt. 100

4. In a lock, a casing, a bolt slidably mounted in said casing, means for projecting said bolt, a second bolt mounted in said casing, and means for causing said second bolt to first slidably move in one direction, then rotate about a portion thereof and then slidably move in an opposite direction, during the projection of said first bolt. 105

5. In a lock, a bolt, means for moving said bolt for projecting the same, a second bolt, and means associated with said bolts for causing sliding movement of said second bolt during a part of the projecting movement of said first bolt 115 and for causing rotation of said second bolt during another part of the projecting movement of said first bolt and for causing sliding movement of said second bolt during still another part of the projecting movement of said first bolt. 120

6. In a lock, a casing, a horizontal bolt slidably mounted therein, means for moving said bolt and projecting the same, a vertical bolt and means associated with said bolts for causing sliding movement of said vertical bolt during part 125 of the projecting movement of said horizontal bolt and for causing rotation of said other bolt during another part of the projecting movement of said horizontal bolt and for causing sliding movement of said vertical bolt during still another part of the projecting movement of said horizontal bolt, said means including a member pivoted to said casing and having a slot, a pin on said horizontal bolt extending within said slot, said horizontal bolt engaging said vertical bolt, 130 and said slot having a portion extending radially with respect to the pivotal connection for said member, and portions extending from said first portion and inclined thereto. 135

7. In a lock, a bolt, means for reciprocating said bolt, a second bolt having a portion mounted for sliding movement only in a direction transverse to the movement of said first bolt, and a second portion rotatably and non-slidably mounted on said first portion, and means associated 140 with said bolts for causing sliding movement of both of said portions and then causing rotation of said rotatably mounted portion, and then causing sliding movement of both of said portions during one stroke of said first bolt. 145

8. In a lock, a casing, a horizontal bolt slidably mounted therein, a U-shaped bolt having an arm slidably mounted in said casing for movement in a direction transverse to the movement of said horizontal bolt, and a portion rotatably mounted on said arm, means for projecting said horizontal bolt, then rotative movement of said rotatably mounted portion, and then inward movement of said U-shaped bolt during the projecting movement of said horizontal bolt. 80
9. In a lock, in combination, a casing, a horizontal bolt slidably mounted therein, said horizontal bolt having a pair of parallel walls, a member slidably mounted between said parallel walls for movement in a direction transverse to the movement of said horizontal bolt, a pin fixed to said member, a tension spring having a portion coiled about said pin, and a pair of arms, one arm contacting said member and the other arm lying against said member, one of said parallel walls having a notch for receiving said second arm for retaining said slidably mounted member on said horizontal bolt, and a member pivoted to said casing at one end thereof, and to said slidably mounted member at the opposite end thereof. 90
10. In a lock, in combination, a casing having an end wall formed with an opening, a horizontal bolt slidably mounted within said casing and adapted to be projected through said opening, said casing having a tubular opening adjacent said end wall, a second bolt slidably mounted within said tubular opening for movement in a direction transverse to the movement of said first bolt, said second bolt having a portion adapted to extend beyond said end wall, said end wall being formed with a groove for receiving the portion of said bolt extending beyond said end wall. 105
11. In a lock, in combination, a casing, a horizontal bolt mounted therein, a vertical bolt comprising a portion slidably mounted in said casing for movement in a direction transverse to the movement of the horizontal bolt, and a portion rotatably and non-slidably mounted on said first portion, a portion of said rotatably mounted portion extending within said casing in the retracted position of said horizontal bolt, and means for projecting said vertical bolt to bring said rotatably mounted portion beyond said casing, and then rotating said rotatably mounted portion and then retracting said vertical bolt to bring a portion of said rotatably mounted portion again within said casing during the projecting movement of said horizontal bolt. 110
12. In a lock, in combination, a casing, a bolt slidably mounted therein, a member slidably mounted on said bolt for movement in a direction transverse to the movement of said bolt, a pin fixed to said member, a coil tension spring having a portion coiled about said pin, and a pair of outstanding arms forming the ends of said spring, one of said arms contacting said member and the other arm lying against one face of said member, said horizontal bolt having a portion formed with a notch for receiving said second arm to retain said slidably mounted member on said bolt. 115
13. In a lock, in combination, a casing having an opening, a bolt having a portion slidably mounted within said opening, and a portion extending at an angle to said first portion and disposed exteriorly of said casing, said casing being formed with a groove on the outer surface thereof, and means for causing sliding movement of said bolt for moving said second portion thereof into said groove. 95
14. In a lock, in combination, a casing having an opening, a bolt having a portion slidably mounted within said opening, and a portion extending at an angle to said first portion and disposed exteriorly of said casing, said casing being formed with a groove on the outer surface thereof, and means for causing sliding movement of said bolt for moving said second portion thereof into said groove, and means for causing rotation of said second portion of said bolt. 100
15. In a lock, in combination, a casing having an end wall formed with an opening, a bolt slidably mounted within said casing and adapted to be projected through said opening, a second bolt having a portion slidably mounted on said casing for movement in a direction transverse to the movement of said first bolt, said casing being formed with a groove on the outer surface thereof and adjacent said end wall, said second bolt having a portion adapted to be received within said groove, and means for causing sliding movement of said second bolt for bringing the second portion thereof into and out of said groove, and means for rotating said second portion of said second bolt. 110
